MOUNTING FOR A RIFLE TELESCOPIC SIGHT

Irving Rubin, 21781 Stratford, Oak Park, Mich. 48237,
and Ivan Jimenez, 1780 Outerlane Drive, Ypsilanti,
Mich. 48197

Filed Feb. 26, 1970, Ser. No. 21,641

Term of patent 14 years

Int. Cl. D22—02

U.S. Cl. D22—7

FIG. 1

FIG. 2

FIG. 3

FIG. 4

FIG. 5

FIG. 6

FIG. 1 is a plan view of a mounting for a rifle telescopic sight showing our new design;

FIG. 2 is a side view thereof, the opposite side view being a mirror image;

FIG. 3 is a front elevational view thereof, the rear elevational view being a mirror image of this elevation;

FIG. 4 is a bottom view thereof;

FIG. 5 is a front and right side perspective view thereof; and

FIG. 6 is a rear and left side perspective view thereof.
We claim:

The ornamental design for a mounting for a rifle telescopic sight, as shown and described.
